APPARATUS FOR CONCENTRATING
SULPHURIC ACID

John Bachi, Whiting, Ind., assignor to Standard
Oil Company, Chicago, Ill., a corporation of
Indiana

Application November 2, 1936, Serial No. 108,755

2 Claims. (Cl. 23—275)

The present invention relates to the concentration of sulphuric acid and relates more particularly to the treating of sludge acids or separated sludge acids obtained in the refining of petroleum oils or their fractional distillates.

In the use of multiple stage acid concentrators of the general type shown in the patent to Heckenbleikner 1,991,745, granted February 19, 1935, it has been found that the practice of using "Duriron" downcomer pipes for introducing the hot gases into the different stages—particularly the weak stage—results in the breakage of a large number of these pipes. The frequent breakage of these "Duriron" downcomer pipes is attributed to the impact of coke thereagainst. This coke forms in the weak stage due to decomposition of sulphonic acids and tar. "Duriron" pipes are very expensive and their replacement involves a considerable loss of time. The frequent replacement of downcomer pipes has thus become a large factor in lowered efficiency of operation.

It is a particular object of the present invention to provide an acid concentrating vessel with an improved means for causing contact between the hot gases introduced into the vessel and the liquid contained therein.

It is a further particular object of the present invention to provide an improved arrangement which will take the place of the conventional "Duriron" downcomer pipes, particularly in the weak stage of an acid concentrator.

My invention will now be described more particularly with reference to the accompanying drawings in which:

Figure 1 is a top plan view of the concentrator embodying my invention;

Figure 2 is an elevation of a transverse cross-section of the apparatus shown in Figure 1 showing the auxiliary wall of my invention;

Figure 3 is a cross-section taken on line 3—3 of Figure 2; and

Figures 4 and 5 are cross-sections showing two modified forms of auxiliary wall.

Referring particularly to Figures 1 and 2, I have illustrated a furnace 1, a strong acid chamber 2 and a weak acid chamber 3, disposed in series relation, together with conduits 4, 5 and 6, for conducting hot gases overhead from the furnace into said respective acid chambers. An exhaust conduit 7 leads from the weak acid chamber to the conventional Cottrell precipitator (not shown). Suitable conduits 8, 9 and 10 are provided for introducing acid to and withdrawing acid from the respective vessels and for main-

taining a definite liquid level therein. The two acid chambers are closed vessels except for openings providing for reception of the above referred to conduits. The specific construction of the apparatus thus far described may take the form shown in the patent to Heckenbleikner, comprising a horizontal cylindrical or drum shaped steel tank 11 provided with a lining of acid proof masonry 12. The drum or shell is divided into two separate chambers 2 and 3 by means of an integrally formed separating wall 13. This results in two vessels defined by enclosing walls and disposed in series relationship, the separating wall being common to both vessels. The furnace delivers hot gases to a pair of conduits 4 and 5, one of which, 5, extends directly to the weak acid stage and delivers these gases into the first vapor space 21 of the weak acid stage. The other conduit extends directly into the strong acid stage where the gases are caused to bubble through the strong acid. The gases then pass to the first vapor space 21 of the weak acid stage through the overhead conduit 6. Valve means are provided for determining distribution of the gases delivered from the furnace to each of the above two conduits. The arrangement so far described is conventional.

Again referring to Figure 2, it will be seen that I have provided an auxiliary wall 14 in combination with the defining walls of the weak acid vessel. This wall is formed as a continuation of the acid proof masonry lining 12 and extends entirely across the vessel and divides the vapor space above the liquid level into two chambers. This wall extends below the surface of the liquid and presents a transverse linear baffle edge 15 to the passage of gases from the vapor space on one side to the vapor space on the opposite side of the wall, all of the gases passing in the direction indicated by the arrows. This wall is not subject to breakage as are the "Duriron" downcomer pipes shown in the Heckenbleikner patent, since this wall is more rigidly supported within the vessel, i. e., formed integral with the acid proof masonry lining and extending completely across the vessel as shown in Figures 3, 4 and 5. The provision of this auxiliary wall 14 in combination with the enclosing walls of the acid vessel makes it unnecessary to replace the broken "Duriron" downcomer pipe shown in Figure 2.

In Figure 3 I have shown in greater detail the auxiliary wall 14 of Figure 2. A masonry wall is shown supported by a masonry arch 16. A relatively large radius is employed for the supporting arch 16 in order that the lower face 15 thereof

present a substantially horizontal baffle edge to the passage of gases therebeneath.

Figure 4 shows an alternative form of baffle wall. The masonry work is supported by a 5 "Duriron" member 17 which engages the opposite walls of the vessel and which is reinforced by a second "Duriron" member 18, which in turn supports the first "Duriron" member near its mid-portions.

10 Figure 5 is another alternative form of construction for my auxiliary wall. In this modification, the auxiliary wall extends all the way to the bottom of the vessel, but is constructed with openings 19 therein, which openings present 15 a baffle edge 20 below the surface of the liquid for the purpose already noted.

I have illustrated my auxiliary wall as being constructed of acid proof brick (Figures 3 and 5) or acid proof brick and "Duriron" supporting 20 means (Figure 4) but it is apparent that any well-known material which has the necessary strength and acid-resisting characteristics may be employed. Obviously other specific forms of 25 constructing this wall to give the resulting baffle edge disclosed may be employed without departing from the spirit of my invention.

In the operation of my acid concentrator all of 30 the hot gases delivered to the first vapor space 21 in the weak acid chamber are forced to bubble through the liquid and under the baffle edge 15 of the auxiliary wall, and hence into the second vapor space 22 on the opposite side of the auxiliary wall. From this vapor space the hot gases 35 pass by way of a conduit to a Cottrell precipitator (not shown).

It will be seen that I have provided an improvement 40 in acid concentrating apparatus which makes it possible to eliminate the expensive "Duriron" downcomer pipes. This improved arrangement may be added to present apparatus without 45 modifying its existing structure. The auxiliary wall which I have disclosed effects a more extensive and even distribution of contact between the hot gases and the liquids. This larger area of contact results in a reduction of the blower pressure necessary to force a given volume of gas 50 through the vessel. The new and improved results thus effected mean a marked increase in efficiency of operation.

50 While I have described my invention in connection with certain specific embodiments there-

of, it is to be understood that these embodiments are offered by way of illustration, rather than by way of limitation, and that I do not mean to be limited thereby except as indicated in the scope of the appended claims which should be construed as broadly as the prior art will permit. 5

I claim:

1. Acid concentrating apparatus including a furnace stage and a plurality of concentrating stages, conduit means for directing hot gases from said furnace stage successively to said concentrator stages in series, conduit means for conducting the gases from the vapor space of each concentrator stage to the vapor space of the succeeding stage, additional conduit means for bypassing a portion of the hot gases from the furnace stage directly to the vapor space of a subsequent stage beyond the first of said series stages, means in said subsequent stage forming a confined space above the acid level for the reception 20 of both said series stream and said bypass stream, said means comprising an auxiliary baffle wall composed of acid-resisting material extending completely across the interior of said stage and presenting a linear baffle edge below the surface 25 of the acid, said baffle edge being effective to produce intimate and extensive contact between said gases and said acid.

2. Acid concentrating apparatus including a furnace stage for heating a supply of gases under 30 pressure, a concentrator stage containing relatively strong acid, a concentrator stage containing relatively weak acid, conduit means for directing hot gases from said furnace stage to said strong acid concentrator stage, conduit means for 35 conducting gases from the vapor space of the strong acid stage to the vapor space of the weak acid stage, additional conduit means for bypassing a portion of the hot gases from said furnace stage directly to the vapor space of said weak 40 acid stage, means in said weak acid stage forming a receiving space above the acid level for the reception of both said series stream and said bypass stream, said means comprising an auxiliary baffle wall composed of acid resisting material extending completely across the interior of said 45 stage and presenting a linear baffle edge below the surface of the acid, said baffle edge being effective to produce intimate and extensive contact between said gases and said acid.

JOHN BACHI.
